OSCILLATOR CIRCUIT

Clarence W. Hansell, Port Jefferson, N. Y., assignor to Radio Corporation of America, a corporation of Delaware

Application April 24, 1941, Serial No. 390,039

9 Claims. (Cl. 250—27.5)

The present invention relates to a magnetron oscillator electron discharge device, and particularly to such a device adapted for the generation of very short waves.

An object of the present invention is to provide a simplified mechanical arrangement for the anode electrode of the magnetron by means of which the anode itself forms a tuned circuit located entirely within the envelope of the magnetron tube.

A further object is to provide a compact and efficient magnetron tube for use at ultra short waves which is characterized by reduced losses in the anode circuit.

Another object is to provide in a magnetron a compact and completely enclosed anode tuned circuit whose natural frequency corresponds to the electron oscillation frequency.

In the magnetron electronic oscillators of the prior art, the velocities of electrons taking part in the oscillation have usually ranged up to a maximum of only about 10% of the velocity of light, corresponding to anode to cathode potentials up to about 3000 volts. The average velocities of electrons around their orbits from the cathode out to the vicinity of the anode and back to the cathode have been somewhat less than 10% of the velocity of light. As a consequence, the frequency of the electronic oscillations has usually been much lower than would be the resonant frequency of a slotted cylindrical anode for oscillations in a circumferential direction around the cathode, and heretofore it has not been recognized that the anode might be made resonant circumferentially to the frequency of the electronic oscillations.

The present invention recognizes this possibility and provides the means to accomplish it.

In accordance with the present invention, there is employed an electronic oscillator in which the anode itself forms a tuned circuit and is in the form of a spiral coil of sheet metal extending circumferentially about the cathode for a distance of more than one turn. The ends, or turns of the coil are made to overlap in physically spaced relation, so that only the innermost turn receives the electrons emitted from the cathode. By employing a coil of predetermined dimensions, the anode becomes a half wave oscillator with oscillations taking place circumferentially around the anode. Putting it another way, the anode is constructed to have such inductance and such capacitance that it forms a circuit resonant to the electron oscillation frequency or a harmonic thereof. The term "electronic oscillator" is used herein to designate an oscillator in which the transit time of the electrons is coordinated with the frequency of oscillations.

By constructing the anode in accordance with the invention, the current in the anode circuit has available a very wide current path, as a con-

sequence of which there are less losses than would be the case if there were employed the customary externally located tuned circuit with its associated connecting leads. The overlapping of the anode turns, in accordance with the invention, also permits tuning the anode to a frequency lower than can be obtained in the known types of magnetron circuits which employ split cylinder anode segments.

10 A more complete description of the invention follows in conjunction with a drawing, in which Figs. 1 and 2 show, by way of example only, cross sections, at right angles to the axes, through two magnetron electron discharge devices constructed in accordance with the principles of the present invention.

Referring now to the drawing, the magnetrons shown in Figs. 1 and 2 comprise an enclosing glass envelope 1, having therein a filamentary cathode 2, and surrounding the cathode a coiled anode indicated as 3 in Fig. 1 and as 4 in Fig. 2. The cathode 2 is disposed within the anode and may be a linear filament of suitable construction having leading-in conductors (not shown) secured at its ends. The glass envelope 1 may be encompassed by a field coil 5 which is coaxial with the filament 2 and may be utilized to produce a magnetic field parallel to the filament and at right angles to the cross sections shown in the figures. A positive potential is maintained on the anode, with respect to the cathode, by means of connections (not shown) in the same manner as for conventional magnetrons.

The anode of Fig. 1 comprises a ribbon or sheet of metal substantially cylindrical (as shown) and having overlapping sections designated X and Y. By suitable choice of the dimensions of the anode and the amount of overlap and spacing at X and Y, there is obtained a desired circumferential natural period for the anode which tunes the anode to the electron oscillation frequency; or, if desired, to a harmonic of the electron oscillation frequency. In effect, the anode is thus made to be a one-half wave oscillator upon which oscillations take place circumferentially. The coiling or curving of the anode strip or sheet, and the combining of the functions of anode and resonant circuit in a single element results in a very compact electron discharge device oscillator 50 whose dimensions are considerably smaller than those of conventional magnetron oscillators.

Assuming that oscillations are taking place, there will be a radio frequency current flowing around the anode which periodically adds to or 55 opposes the magnetic field set up by the external field coil. The periodic fluctuation in magnetic field will tend to vary the paths of the electrons just as the fluctuations in external field current controls the path of electrons in long wave 60 magnetron oscillations. This fluctuation in magnetic field strength may add to the forces respon-

sible for oscillation which are present in ordinary magnetron tubes. In fact, if the anode oscillating current is great enough, the fluctuating magnetic field may become a primary factor in the production of oscillations. In this case the frequency of the oscillations will become less dependent upon electron transit time and will depend more upon the circumferential natural period of the anode.

The circulating current around the anode will not be uniform but will be maximum at the point marked Z in Fig. 1. Point Z is substantially half way between the two ends of the anode. Also, the current and magnetic field fluctuations will be 90° out of phase with the voltage difference between X and Y. To explain one reason for oscillation, let us assume that at a given instant the current at Z is a maximum and is carried by electrons in the direction of X as indicated by the arrow immediately beneath Z. Then electrons moving from the filament to the anode, starting toward Z, will have their paths bent relatively little and will tend to follow some such path as that marked B. When the current at Z is a maximum in the reversed direction toward Y, then the electron path will follow one like that marked A. Electrons leaving the filament when the current at Z is maximum, or a little before, will be passing X perhaps three-quarters cycle later when X is most positive. The positive potential of X will then tend also to pull out the path of the electron. The combination of fluctuations in magnetic field and potential on X will then vary the current flow to point Y with such a phase relation as to produce oscillation.

Fig. 2 shows an arrangement of a magnetron electron discharge device in which there is obtained circumferential oscillations of lower frequency, obtainable with lower anode to cathode direct current potentials. The system of Fig. 2 uses an anode in the form of a spiral coil of considerably more than one turn. The individual turns are suitably spaced from one another and are composed of a ribbon or sheet of metal suitably dimensioned to give the desired tuning effect in relation to the electron oscillation frequency. Such a construction permits designing the magnetron with much less spacing from cathode to anode, for a given wavelength, and decreases the overall tube dimensions.

To take oscillatory power from either of the magnetrons of Figs. 1 and 2, one may utilize radio wave radiation coming directly from the oscillating anode, or, preferably, connections may be made either directly, or by induction, to the anode by means of conductors over which wave power may be transferred to a point of utilization. In Fig. 2, I have shown conductors 8 connected to the anode which may be used to modify the anode resonant frequency. In practice, these conductors are likely to range above and below a quarter wave in length. They may be coupled to a transmission line 7, or any other load circuit, as shown. Bridged across leads 8, there is shown an adjustable position bypass condenser 9 composed of a pair of spaced loops coupled together and which are slidable on the leads 8.

Although I prefer utilizing a single anode made of one piece of metal, I may also employ two or more overlapping pieces, each tuned to the oscillating frequency, taking into account the mutual effects between them.

What is claimed is:

1. A magnetron electronic oscillator having a linear cathode and an anode in the form of a cylindrically shaped sheet or ribbon of metal of more than one turn and having overlapping portions, the dimensions and arrangement of said anode being such that its circumferential natural period corresponds to the electron oscillation frequency or a multiple thereof.

2. A magnetron electronic oscillator having a linear cathode, and an anode in the form of a coiled sheet of metal of more than one turn and having overlapping portions, the dimensions and spacing between turns of said anode being such that it is resonant in a circumferential direction to the electron oscillation frequency or a multiple thereof.

3. A magnetron electronic oscillator having a linear cathode and a single part anode in the form of a substantially cylindrically shaped sheet or ribbon of metal with overlapping, though spaced ends, said overlapping being in a circumferential direction, the dimensions of said anode and the degree of overlap being such that the anode is tuned to a circumferential natural period which corresponds to the electron oscillation frequency or a multiple thereof, and a coil surrounding said anode for producing a magnetic field parallel to said cathode.

4. An electronic oscillator having a cathode and an integral anode structure surrounding said cathode, said anode comprising a coiled metallic ribbon of more than one turn and having overlapping portions, the dimensions of said anode and its arrangement being such that its circumferential natural period corresponds to the electron oscillation frequency.

5. A magnetron electronic oscillator having a cathode and a single part anode structure surrounding said cathode, said anode comprising a coiled metallic ribbon of more than one turn and having overlapping portions, the dimensions of said anode and its arrangement being such that its circumferential natural period corresponds to the electron oscillation frequency or a multiple thereof.

6. A magnetron oscillator having a linear cathode and a single part anode structure surrounding said cathode, said anode comprising a spiral metallic coil of two overlapping turns, the dimensions and spacing between turns being such that the circumferential natural period of said anode corresponds to the electron oscillation frequency or a multiple thereof.

7. Electron discharge device apparatus having a cathode and a single part anode structure surrounding said cathode, said anode comprising a coiled metallic ribbon of more than one turn and having overlapping portions, the dimensions of said anode and its arrangement being such that its circumferential natural period corresponds to the electron oscillation frequency.

8. An electronic oscillator having an anode in the form of a coiled sheet of metal having overlapping portions circumferentially, the dimensions and spacing between turns of said anode being such that it is resonant in a circumferential direction to the electron oscillation frequency or a multiple thereof.

9. In an electronic oscillator, a cathode, and an anode substantially one-half wave length long circumferentially at the operating frequency surrounding said cathode, said anode comprising a coiled metallic ribbon of more than one turn and having overlapping portions.
